United States Patent Office

Des. 183,436

Patented Aug. 26, 1958

183,436

ELECTRONIC CABINET

James G. Wells, Chicago, and Herbert C. Golz, Aurora, Ill., assignors to Elgin Metalformers Corporation, Elgin, Ill., a corporation of Illinois

Application September 24, 1957, Serial No. 47,842

Term of patent 14 years

(Cl. D26—5)

Fig. 1.

Fig. 2.

Fig. 1 is a perspective view of an electronic cabinet showing our new design; and

Fig. 2 is a top plan view thereof.

The opposite side has substantially the same appearance as the side shown in Fig. 1.

We claim:

The ornamental design for an electronic cabinet, substantially as shown and described.
